UNITED STATES PATENT OFFICE

CHARLES N. COLSTAD, OF ATTLEBORO, MASSACHUSETTS

COMBINED STEERING AND ENGINE CONTROL DEVICE

Application filed August 30, 1930. Serial No. 478,907.

My present invention relates to motor boats, and more particularly to a novel and improved combined steering and engine control mechanism for operating such boats.

5 My invention is particularly applicable to the type of motor boat in which the engine is mounted in the stern portion of the boat, and while the invention is illustrated and described in combination with an inboard motor 10 operated on the outboard motor principle, the invention is also capable of adaptation to motor boats utilizing an outboard motor, or an engine in any part or position in the boat.

An important object of the present invention is the provision of steering mechanism operated on the principle of an airplane stick control, said mechanism being arranged and located within the boat for dual or plural control, that is, control from either of a plurality of stations or points.

This feature of the invention is carried out by providing a plurality of operating sticks or levers, spaced apart, but connected by a common rod, tube, or other device and operable by either of said sticks or levers.

In the present application I have illustrated this uniting member as a tube, for purposes which will be hereinafter more fully pointed out. This tube is preferably mounted in suitable bearings on the center line of the boat, and adjacent to the bottom thereof, a control stick or lever being fixed to said tube adjacent to each end thereof. Fixed to the bottom of one of said sticks or levers, preferably the 35 rearmost one, is a grooved quadrant, to which is fixed the steering ropes or cables. Suitable pulleys are provided within the boat over which the steering cables run, said cables being attached, at their other ends, to a grooved quadrant fixed to the rudder of the boat.

The operating quadrant is positioned perpendicular to the longitudinal axis of the boat, and in a vertical plane, the operated quadrant being also positioned perpendicular to the longitudinal axis of the boat, but in a horizontal plane or position. Thus movement of either of the sticks or levers laterally of the boat will effect winding of the steering cable upon the quadrant and a drawing of the rudder toward the same side

of the boat to which the stick or lever has been moved. In other words, to steer the boat, the stick or lever, or either of them is moved in the direction in which it is desired that the boat shall turn. Thus, in a 55 boat of the type illustrated herein, having a plurality of compartments, the steering of the boat may be effected from either compartment with equal ease and efficiency. In order to effect turning of the boat, while under way, 60 with a minimum of movement of the control stick or lever, I preferably vary the ratio between the operating quadrant and the operated quadrant, the ratio as shown in the present drawings being substantially 2 to 1. 65 This represents a more efficient method of steering than by looping the steering cables or ropes over additional pulleys, and doubling up on the said cables.

Many boats of the type illustrated here- 70 in are constructed, adapted and intended for relatively high speeds, and in order to achieve these speeds with a minimum of engine power, the boats are constructed to plane as the engine speed is increased. In 75 a multi-compartment boat, for example, the boat is best balanced for most efficient operation, when only one person is aboard, by said person being located in a compartment remote from the engine. This is not feasible 80 in boats of this type, due to the location and arrangement of the engine controls, that is, the ignition switch, starter switch, spark control, and throttle.

An important object of the present invention, therefore, resides in providing means or mechanism for operating all of the aforesaid controls by either of the control sticks or levers before mentioned, from either of a plurality of separated points of operation. 85

In order to accomplish this desirable feature of my invention, I unite each of the control sticks or levers by means of a rod 90 preferably passing through the control tube above referred to. Each of the control sticks or levers is pivoted, at a second pivot point, above the first mentioned pivot point, said first pivot point being the point on which the sticks or levers rotate to effect steering of the boat. To one of the control sticks, pref- 100

erably the rearmost one, I affix a rod projecting rearwardly, and which rod would be the engine control rod were it not for the fact that because of the lateral oscillation of the control sticks or levers it becomes necessary to interpose means between said control sticks and the engine so that the engine controls will be unaffected by lateral oscillation or movement of the control sticks. I accomplish this result by pivotally mounting a link between the control stick to which the rearwardly extending rod inclines upwardly from the bottom of the rearmost control stick to a point on said link which is in alignment with the lateral pivot point of said control stick. Thus lateral movement of the control stick will not effect any movement of the link to disturb the engine controls. From the upper end of the link referred to a rod extends rearwardly and is connected at its rearmost end to a T-shaped lever having three arms thereon, said lever being mounted on but freely rotatable about the butterfly valve shaft which extends through the carburetor.

The said rod is fixed to one arm of said T-shaped lever, and to another arm of said lever is fixed a spark control rod operating the timer or distributor to advance or retard the spark. To the third arm of said T-shaped lever is affixed an L-shaped rod having an eye in the free end thereof. Through this eye extends a rod fixed to the ignition switch shut-off button. The starter switch 35 may be either manually controlled or, as will be hereinafter more fully explained, automatically controlled. Thus, movement of either of the control sticks or levers longitudinally of the boat will perform a plurality of functions. It being assumed that the starter switch has been closed, and that the engine is running, movement of either of the control sticks will effect a pulling forward of the T-lever operating rod, which will advance the spark, and will open the butterfly valve in the carburetor by means of a connection between the T-lever and the butterfly valve shaft, said connection to be so arranged that when the butterfly valve has reached its wide open position, there will still be permitted movement of the spark control rod to still further advance the spark, if desired, or necessary. During this forward movement of the T-lever operating rod, the ignition switch button control rod will be moved without effecting the ignition switch. However, on movement of the control stick or lever, or either of them, rearwardly, the T-lever operating rod will be also forced to the rear, through the medium of the interposed link, closing the butterfly valve, and retarding the spark, and, at a predetermined moment, pushing the ignition switch button to shut off the ignition. If desired, I may provide means associated with the ignition

switch to control the starter switch, so that the starter switch can also be closed by operation of the control stick or lever without manual operation of the starter switch button.

I believe that the dual steering control mechanism above briefly described is novel, and I have, therefore, claimed the same broadly herein.

I also believe that the engine control mechanism illustrated herein and above briefly described, is novel, and have, therefore, claimed this feature broadly in this application, together with the feature of dual operation thereof.

I furthermore believe that the combined steering and engine control mechanism is novel, as well as the dual operating thereof, and have claimed these features also broadly herein.

Other features and objects of the invention reside in the particular construction and arrangement of my novel mechanism, and the above and other features, details of construction, combinations of parts, and advantages, will be hereinafter more fully pointed out, described and claimed.

Referring to the drawings, illustrating a preferred embodiment of the present invention,

Fig. 1 is a top plan view of a boat in which my invention is embodied;

Fig. 2 is a side elevation, partly in section, of said boat;

Fig. 3 is a cross-sectional view on the line 3—3 of Fig. 2;

Fig. 4 is a cross-sectional view on the line 4—4 of Fig. 1;

Fig. 5 is an enlarged cross-sectional view on the line 5—5 of Fig. 1; and

Fig. 6 is a fragmentary detail view illustrating the automatic starter switch control device.

Referring now to the drawings for a particular description of the invention, its construction and operation, my invention is illustrated as embodied in a boat comprising a hull 1, said boat being divided into a plurality of compartments such as A and B by a vertical lateral partition C, and a rear engine house compartment D being defined by the vertical lateral partition E and the stern boards F. A plurality of frames or ribs 2, 2 are provided, and on certain of these ribs are mounted bearings 3, 3. Rotatably mounted in the bearings 3 is a tubular member 4, one end of said tube 4 projecting beyond each of the bearings 3. A plurality of control sticks or levers 5 and 6 are provided, each having a bracket 7 and 8 respectively depending therefrom and said brackets being fixed to the tube 4. Thus, lateral oscillation of either of the levers 5 and 6 will effect a simultaneous lateral oscillation of the other lever through the medium of the connecting tube 4. The up-

per portion of the lever 6 is removable, being threaded into its lower section 9, as illustrated at 10. Thus, if it is desired to manipulate the boat from the compartment B the lever 6 may be unthreaded from its base 9 and thus will not be in the way of passengers in the compartment A.

On the bottom of the bracket 7, and preferably integral therewith, is a quadrant 11, in the grooves of which are fixed the ends of steering cables or ropes 12 and 13. The steering cable 12 passes over pulleys 14 fixed on the starboard side of the boat and extends to a quadrant 15 fixed on the top of the rudder 16. The cable 13 passes over pulleys 17 fixed on the port side of the boat and extends also to the quadrant 15. The quadrant 15 is provided with grooves similar to the quadrant 11, and the cables 12 and 13 are located in different grooves and fixed to opposite ends of the said quadrant.

To simplify manipulation of the rudder 16, with a minimum of movement of the levers 5 or 6, I decrease the ratio between the quadrant 11 and the quadrant 15, the ratio of the quadrant 11 to the quadrant 15 in the drawings of the present application being substantial. Thus, any movement of the quadrant 11 will be substantially increased when transmitted by the cables 12 or 13 to the quadrant 15 and hence to the rudder 16. It will thus be seen that the rudder 16 can be readily controlled by an operator seated either in the compartment A or the compartment B. For example, if the operator is seated in the compartment A, movement of the lever 6 laterally of the boat will effect a rotation of the tube 4 in its bearings 3, and hence a resulting lateral rotation of the quadrant 11. In steering the boat, the levers 5 or 6 are oscillated in the direction in which it is desired to turn the boat. For example, referring to Fig. 1, and assuming that the boat is under way, and that it is desired to turn or swing the boat to the left, either of the levers 5 or 6 will be moved toward the port side of the boat. This will effect a counter-clockwise rotative movement of the quadrant 11, when viewed from the stern of the boat, and will draw the cable 13 over the pulleys 17, thus pulling the quadrant 15 and rudder 16 toward the port side of the boat, and resulting in a turning of the boat to the left. The simplicity and efficiency of my novel steering control mechanism will be instantly apparent to those skilled in the art.

In the compartment D is housed a motor designated generally at 18, this motor resting on an engine bed 19 supported by cross frames 20 and being secured to said bed by studs 21 and nuts 22, or in any other desirable manner. Communicating with the engine 18 is a carburetor 23 within which is mounted a butterfly valve 24 on a shaft 25. Mounted for free rotation about the shaft 25

is a T-shaped lever comprising three arms 26, 27 and 28. Fixed to the arm 26 is a rod 29 which extends forwardly through an aperture 30 in the partition E and is rotatably attached to the upper end of a link 31, said link 31 being pivotally connected at 32 to a bracket 33 fixed to the bed 19 by a screw 34, or in any other desirable manner.

A rod 35 is pivotally connected to the bottom end of the link 31 and extends forwardly and is fixed to the bottom of the projection 36 depending from the lever 5, said lever 5 being pivotally mounted on its bracket 7 at 37. A second rod 38 extends through the tube 4, and is connected to the depending projection 36 on the lever 5 and to the depending projection 39 on the lever 6, the lever 6 being pivotally mounted at 40 in its bracket 8. An arm 41 is fixed on the butterfly valve shaft 25, and a bolt 42 extends between the arm 41 and the arm 26 of the T-lever, a spring 43 being interposed between the arm 26 and the arm 41. A tube 44 is fixed at one end to the carburetor 23 and at its other end to the head 45 of the engine 18. Fixed at one end to the arm 27 is a spark control rod 46 which extends through said tube 44 and is fixed at its other end to a timer or distributor in the head 45. Fixed to the engine 18 by a suitable bracket 47 is a starter and ignition switch box 48, having a button 49 at one end accessible through an aperture 50 in the partition E, and having a shut-off button 51 at its opposite end.

Projecting outwardly from the shut-off button 51 I provide a pin 52, and also provide an L-shaped rod 53 secured at one end to the arm 28 and provided with an eyed portion 54 on its opposite end, the pin 52 projecting through the eye 54.

The button 49 is illustrated in Fig. 5 as having been depressed, to start the motor, and the controls are illustrated in substantially half open or advance position. Assuming now that the operator desires to increase the speed of the boat, either the lever 5 or lever 6 will be pushed forwardly. This movement will effect a rocking of the link 31 and a drawing forward of the rod 29, rotating the T-shaped lever about its pivot 25. This forward movement of the rod 29 will effect a further opening of the butterfly valve 24 through the medium of a spring 43, and arm 26, simultaneously moving the arm 27 downwardly and drawing the spark control rod through the tube 44, to advance the spark. It may be desirable, after the butterfly valve 24 has reached its wide open position, to still further advance the spark, and this is provided for by the spring 43. After the butterfly valve 24 has reached its wide open position further forward movement of the lever 5 or 6, will effect a continued pull on the rod 29, rotating the T-lever about its pivot 25

and forcing the arm 26 to the right against the tension of the coiled spring 43, thus permitting the rod 46 to be drawn still further downwardly to advance the spark.

10 The forward end of the rod 35 is fixed to the bottom of the projection 36 of the lever 5 to provide as much travel as possible about the pivot point 37, and the forward end of the rod 35 being located below the horizontal pivot point of the lever 5, necessitates the interpositioning of the link 31 between the engine controls and lever 5.

15 The point of union between the rod 35 and link 31 is on the same plane as the center of the lateral pivot point of the lever 5. Thus lateral oscillation of the lever 5 will move the end of the rod 35 which is fixed to the projection 36 throughout an arc, but will have no effect on the link 31 or rod 29, thus 20 permitting steering of the boat without disturbing any of the engine controls, and also permitting simultaneous steering of the boat and operation of the engine controls at desired speed.

25 When it is desired to stop the engine the lever 5 or 6 is pulled rearwardly, thus effecting a push rearwardly on the rod 29, closing the butterfly valve 24, retarding the spark through the medium of the rod 46, and, on 30 still further pulling of the lever 5 to the rear, the eyed portion 54 of the L-shaped rod 53 will engage the shut-off button 51 and press the same into the switch box 48, cutting off the ignition and stopping the engine.

35 It may be desired to have the starter switch automatically controlled to start the engine, and to provide for this I position on the pin 52 a collar or stop 55 attached in predetermined position by a set screw 56, and position 40 a coiled spring 57 on the pin 52 between the stop 55 and the eyed end 54 of the L-shaped lever 53. Thus, when it is desired to automatically start the engine, movement forward on either control lever 5 or 6 will open 45 the butterfly valve and advance the spark to a predetermined extent, meanwhile compressing the spring 57 against the stop 55. When the tension of the spring becomes sufficient, it will force the pin 52 to the left, drawing the starter button 49 into or toward 50 the box 48, and operating the self-starter.

When this occurs, the pin 52 and stop 55 will be shot a short distance to the left, permitting the spring 57 to again open, and providing for travel of the eyed portion 54 from the position illustrated in Fig. 6 until the coiled spring 57 has been completely compressed. When utilizing this automatic 60 starter control the engine will be shut off in the same manner as above described.

It will thus be instantly understood and appreciated that I have devised a simple and efficient combined steering and engine operated mechanism, as well as a novel dual

control arrangement for use in connection therewith.

The fact of being enabled to operate all of the engine controls, as well as the steering of the boat, by a single member, the ease 70 and simplicity of operation of such member, and the desirability of being enabled to operate the boat without paying attention to the individual engine controls, will appeal to operators of these boats and to others skilled 75 in this art.

While I have necessarily described my present invention somewhat in detail, it will be appreciated that I may vary the size, shape, and arrangement of parts within reasonably wide limits without departing from the spirit of the invention.

My invention is further described and defined in the form of claims as follows:

1. A steering control device of the kind described, comprising a boat, a rudder, a plurality of spaced apart levers pivotally mounted for oscillation laterally of said boat and connected for independent simultaneous operation, a quadrant fixed to one of said levers, a quadrant fixed to said rudder, a flexible element uniting said two quadrants, whereby manipulation of either of said levers will operate said rudder.

2. A steering device of the kind described, comprising a boat, a rudder, a plurality of spaced apart levers pivotally mounted for oscillation laterally of said boat, a quadrant fixed to one of said levers, a quadrant fixed to said rudder, flexible elements uniting said quadrants, and a shaft on which each of said levers is fixed, whereby manipulation of either of said levers will operate said rudder.

3. A steering control device of the kind described, comprising a boat, a rudder, a plurality of spaced apart levers pivotally mounted for oscillation laterally of said boat, a quadrant fixed to one of said levers, a quadrant fixed to said rudder, flexible elements uniting said quadrants, bearings in said boat, and a shaft rotatably mounted in said bearings, each of said levers being fixed to said shaft, whereby manipulation of either of said levers will effect a rotative movement of said first quadrant and consequent operation of said rudder.

4. In a boat, an engine, a plurality of engine controls, and a plurality of spaced apart devices, remote from said engine and independently operable to simultaneously operate all of said engine controls.

5. In a boat, an engine, a plurality of engine controls, a rudder, and a single means to operate said rudder and said engine controls.

6. In a boat, an engine, a plurality of engine controls, a rudder, and a single means to simultaneously operate said rudder and said engine controls.

7. In a boat, an engine, a plurality of engine controls, a rudder, and a plurality of independently operable devices to each simultaneously operate said rudder and said engine controls.
- 5 8. In a boat, an engine, a plurality of engine controls, a rudder, and a lever remote from said engine and said rudder, said lever being pivotally mounted for oscillation laterally of said boat to operate said rudder, and said lever being pivotally mounted for oscillation longitudinally of said boat to operate said engine controls.
- 10 9. In a boat, an engine, a plurality of engine controls, a rudder, and a lever remote from said engine and said rudder, said lever being pivotally mounted for oscillation laterally of said boat to operate said rudder, said lever being pivotally mounted for oscillation longitudinally of said boat to operate said engine controls, and a second lever, spaced from said first lever but so connected thereto that operation of said second lever will also operate said rudder or said engine controls.
- 15 20 25 30 35 40 10. In a boat, an engine, a plurality of engine controls, a rudder, and a lever remote from said engine and said rudder, said lever being pivotally mounted for oscillation laterally of said boat to operate said rudder, said lever being pivotally mounted for oscillation longitudinally of said boat to operate said engine controls, a hollow rotatable shaft on which said lever is fixed, a second lever spaced from said first lever and fixed to said shaft, and a rod fixed at its ends to said levers and extending through said shaft, whereby manipulation of said second lever will also operate said rudder or said engine controls.
- In testimony whereof, I have signed my name to this specification.

CHARLES N. COLSTAD.
